UNITED STATES PATENT OFFICE.

WILLIAM S. AULT, OF WILSHIRE, OHIO.

LAMP-BURNER FOR INCUBATORS.

No. 926,044.

Specification of Letters Patent.

Patented June 22, 1909.

Application filed November 1, 1907. Serial No. 400,222.

To all whom it may concern:

Be it known that I, WILLIAM S. AULT, a citizen of the United States, residing at Willshire, in the county of Van Wert and 5 State of Ohio, have invented new and useful Improvements in Lamp-Burners for Incubators, of which the following is a specification.

This invention relates to automatic lamp 10 burners for use in connection with incubators, the object of the invention being to provide simple and reliable means influenced by the temperature within the incubator for automatically raising and lowering the wick 15 of the lamp and thereby correspondingly increasing or diminishing the heat, thus enabling an equal temperature to be maintained in the incubating chamber at all times.

With the above general object in view, the 20 invention consists in the novel construction, combination and arrangement of parts hereinafter fully described, illustrated and claimed.

In the accompanying drawings:—Figure 25 1 is a vertical longitudinal section through an incubator showing a lamp thereon and operating mechanism for the wick of said lamp embodying the present invention. Fig. 2 is a vertical diametrical section through 30 the burner. Fig. 3 is a similar section taken at right angles to Fig. 2. Fig. 4 is a detail perspective view of the fork and lever at the upper end of the stem of the thermostat. Fig. 5 is a detail perspective view of the 35 tubular wick carrier. Fig. 6 is a detail perspective of the wick adjusting device. Fig. 7 is a detail view of the bearing member of the wick adjusting device.

Referring to the drawing, 1 designates 40 the heating chamber of an incubator of any desired construction and 2 the compartment in which the lamp 3 is located. In carrying out the present invention, the tubular wick holder 4 is mounted to slide up and down 45 within the wick tube 5 of the burner as indicated in Figs. 2 and 3 and is provided with a bearing 6 in which is journaled a wick shaft 7 having one or more star wheels 8 which work through vertical slots 9 in the 50 wick holder 4, as indicated in Figs. 1 and 3.

Projecting from the bearing 6 is an eye 10

receiving one end of a lever 11 which is fulcrumed at 12 on a bracket connected with the frame of the burner, the other end of said lever being provided with a suitable counterbalance weight 13, and a hook or eye 14 to which is connected a chain 15 or other flexible connection which extends upward and is attached to one end of a superimposed lever 16, the said lever being journaled on a 60 fulcrum pin 17 which is carried by a fork 18 on the upper end of a rod or stem 19. The rod or stem 19 extends downward through a tube 20 mounted within the incubator and provided at its lower end with a raised or 65 supporting bracket 21 upon which is mounted a thermostat 22 to which the rod or stem 19 is connected.

23 designates a balance weight which is adjustable on the lever 16 to give the proper 70 poise to the connections which control the operations of the wick carrier 4.

It will be understood in view of the foregoing description that when the temperature within the incubator becomes too high, the 75 thermostat 22 will expand accordingly and move the stem 19 upward thereby raising the lever 16 and operating the lever 11 through the connection 15 thus depressing the wick carrier 4 and lowering the wick 80 and flame. This reduces the heat generating power of the lamp and as the temperature within the incubator increases the thermostat contracts thereby lowering the fulcrum pin 17 of the upper lever 16 and through 85 the connections described operating the lever 11 and again raising the wick. It will thus be seen that the device is entirely automatic after once lighting the lamp. The automatic wick controlling connections, are independent of the usual wick adjusting device and the latter may be operated and set by hand without interfering with the automatic part of the apparatus.

Having thus described the invention, what 95 is claimed as new, is:—

A heat regulator for incubators comprising a lamp burner, a stationary wick tube, a tubular wick carrier movable relatively to the upper end of the stationary wick tube 100 and within the same, a thermostat located within the incubating chamber, operating

connections between said thermostat and wick carrier whereby changes in the temperature of the incubator chamber will automatically effect a sliding movement of the
5 wick carrier toward and away from the upper end of the wick tube, and means independent of said connections for setting the wick consisting of a manually operated

wick-adjusting shaft journaled on and carried by said wick carrier.

In testimony whereof I affix my signature in presence of two witnesses.

WILLIAM S. AULT.
